UNITED STATES PATENT OFFICE.

DAVID M. STIRTON, OF NEW YORK, N. Y.

GARMENT SUPPORTER.

Application filed September 3, 1921. Serial No. 498,284.

To all whom it may concern:

Be it known that I, DAVID M. STIRTON, a citizen of the United States, residing at New York, in the county and State of New York, have made certain new and useful Improvements in Garment Supporters, of which the following is a specification.

The invention relates to garment supporters and more particularly in certain aspects thereof to garment supporters such as are attached to corsets to support the hose.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:—

Fig. 1 is a front elevation of a supporter embodying the invention shown in the same position as when supporting a garment;

Fig. 2 is a detached detail of the outer member of the support;

Fig. 3 is a cross section on the line 3—3 of Fig. 2;

Fig. 4 is a detached detail of the inner member, showing its attachment of the supporting fabric strip;

Fig. 5 is a detached detail of the inner member alone with the roller in section to show the ends of the wire;

Figs. 6 and 7 are detached details of the buckle.

Referring now in detail to the present preferred embodiment of the invention, herewith illustrated by way of example, and describing primarily the embodied form of the outer member of the garment supporter, it comprises a flat back plate 1. This plate has its sides beveled or inclined inwardly and upwardly, and two flanges 2 and 3 extend from said beveled sides, respectively, the flanges being bent forwardly from the back plate 1 and then inwardly or toward each other, to form a receptacle for receiving the inner garment supporting

member, which is described later. The edges, especially the bottom edges, of the flanges 2 and 3 are preferably rounded as shown in Fig. 1 to more readily take the inner member.

In accordance with one feature of the invention, the outer member of the supporter is of rigid material and is lined with a pliable material against which the garment is pressed by the inner member of the support. As embodied, the outer member of the support is of metal and the pliable lining is of fabric, the strip of fabric which supports or carries the outer member being preferably utilized for this purpose. A strip of fabric 8 is attached at its upper end to the shoulder-strap, corset or other garment, and is provided with a buckle 9 to adjust its length. In the loop 10 so formed, a shaped metal loop 11 is hung.

A loop 15 of tape or other suitable fabric is run through this metal loop 11, and from this loop 15 the outer member of the garment supporter is hung. To incorporate the lining feature, slots 16 and 17 are formed in the back plate 1 and these also extend into the bent flanges 2 and 3, and the tape 15 is sufficiently wide at its lower part to extend not only across the back plate 1 but also up along and within the flanges 2 and 3, as best appears from Fig. 3. The two ends of the tape 15 are shown united to the body thereof at 18.

Referring now to the inner member of the garment supporter, it is adapted to form a fit within the upwardly and inwardly inclined lips or flanges 2 and 3 of the outer member and to resiliently press therewithin and thereagainst. As embodied, this inner member comprises a resilient wire loop, having its sides 22 and 23 upwardly and inwardly inclined at the same inclination as, and so as to nest within, the flanges 2 and 3 of the outer member, as already described.

To effect the resilient action, the bottom reach 24 of the loop is open, that is the two ends 25 and 26 are slightly spaced apart, the wire having sufficient spring to exert the necessary supporting pressure on the supported garment. By this construction an efficient pressure sufficient to support the garment is secured irrespective of variations in the thickness of different garments, and the fabric lining of the outer member affords an efficient friction surface on the opposite side of the supported garment.

The resilient loop will also make contact with the outer member throughout its length, which would not be the case if it were of rigid material.

5 Preferably, a hollow roller 27 is mounted on the lower reach 24 of the loop to cover the ends 25 and 26 of the wire. This roller also effects holding and supporting contact with the garment and thus gives additional 10 frictional pressure upon, and support of, the garment.

As shown, the inner member above the garment-supporting side reaches 22 and 23, already described, is brought together into 15 two parallel and substantially contacting parts 30 and 31 and at its top is enlarged into a transversely extending loop 32, which is hung from the wire loop 11 by a bent or hooked metal sheet 33. The spring in the 20 wire of the inner member has its support or fulcrum from this closed-together part just described. The contacting parts 30 and 31 together form a handle or finger-piece for convenient manipulation of the inner member in fastening and unfastening the device. The tape 15 is made somewhat longer than 25 the inner member and its support, to secure the necessary holding action.

Referring now to the means for adjusting 30 the length of the garment or hose supporter, it is designed to lie flat, to prevent creeping from adjusted position, to be easily adjustable, and is without fabric puncturing pins. As embodied, said means comprises a flat 35 plate 36, having a central bar 37 struck up therefrom to receive the end 38 of the fabric therebeneath and to press thereon to hold it firmly in position. On either side of the bar is a slot through the plate, these slots 40 39 and 40, being non-rectilinear across the plate, that is, they are either curved or angled, the central part of the slots being either nearer to or farther away from the bar 37 than the sides or ends of the slots. The fabric held by the bar 37 passes through the 45 upper slot 39 and downwardly on the back of the buckle, passing through the loop 11 and thence from the inside or back of plate 36, through slot 40, and passing across the 50 front of plate 36, it passes again through slot 39 to the back face of plate 36 and thence upwardly to the garment or other article from which it is hung.

The invention in its broader aspects is 55 not limited to the specific mechanisms shown and described but departures may be made therefrom within the scope of the accompanying claims without departing from the principles of the invention and without sacrificing its chief advantages.

What I claim is:—

1. A garment supporter including in com-

bination an outer member having inwardly and upwardly inclined flanges for receiving an inner member and a resilient inner member formed of a loop of wire open at its bottom reach and having its sides upwardly and inwardly inclined to fit within and resiliently press against said flanges to support the garment.

2. A garment supporter including in combination an outer member having inwardly and upwardly inclined flanges for receiving an inner member and a resilient inner member formed of a loop of wire having its sides upwardly and inwardly inclined to fit within and resiliently press against said flanges to support the garment, and a hollow roller on the bottom reach of said loop to assist in supporting the garment.

3. A garment supporter including in combination an outer member having inwardly and upwardly inclined flanges for receiving an inner member and a resilient inner member formed of a loop of wire open at its bottom reach and having its sides upwardly and inwardly inclined to fit within and resiliently press against said flanges to support the garment, and a hollow roller on said bottom reach of said loop to hold the open ends in alinement.

4. A garment supporter, including in combination an outer member having inwardly and upwardly inclined flanges and having a pair of transverse slots extending across the member and into the flanges, a flexible member, substantially as wide as said slots, and threaded through the same, for supporting said outer member and for lining the interior of the said outer member and the interior of the flanges, and an inner member inwardly and upwardly inclined, for fitting within said outer member.

5. A garment supporter, including in combination an outer member having inwardly and upwardly inclined flanges, and a resilient inner member formed of a loop of wire, the lower ends of which are free and the lower sides of which are inwardly and upwardly inclined, and the upper sides of which are in contact for a substantial distance for forming a finger-piece.

6. A garment supporter, including in combination an outer member having inwardly and upwardly inclined flanges, and a resilient inner member formed of a loop of wire, the sides of which press outwardly to lock a garment within the flanges and which yields inwardly to release the garment from the flanges.

In testimony whereof, I have signed my name to this specification.

DAVID M. STIRTON.
